[57] CLAIM

The ornamental design for a wall mounted folding table, as shown and described.

DESCRIPTION

FIG. 1 is a top, front, and right side perspective view of a wall mounted folding table showing my new design, the left side being identical in appearance, and the rear being plain and unornamented;

FIG. 2 is a top, front, and right side perspective view thereof, shown in a partially opened position;

FIG. 3 is a top, front, and right side perspective view thereof, shown in a further partially opened position; and,

FIG. 4 is a top, front, and right side perspective view thereof, shown in a fully opened position.

FIG. 4

FIG. 1
